REACTION PRODUCTS OF PRIMARY FATTY AMINES AND ALDOSE SUGARS

John G. Erickson, Minneapolis, Minn., assignor to General Mills, Inc., a corporation of Delaware

No Drawing. Application November 12, 1952, Serial No. 320,156

6 Claims. (Cl. 260—211)

The present invention relates to new compounds obtained by the reaction of fatty amines with aldose sugars and to the process of producing these compounds. These compounds contain a minimum of two fatty amino groups per molecule and may contain a number of fatty amino groups equivalent to the number of carbon atoms in the aldose sugar. The compounds vary in their properties with the number of fatty amine groups. The lower members of the group (those containing 2 or 3 fatty amino groups per molecule) can be used directly as surface active agents or may be converted into other surface active agents by suitable reactions, such as sulfation, hydrogenation and the like. The compounds containing larger numbers of fatty amino groups may be used to waterproof textiles, either by direct deposition on the fabric or by reaction with formaldehyde and subsequent insolubilization on the cloth.

It is, therefore, an object of the present invention to provide novel reaction products of fatty amines and aldose sugars in which the compounds contain at least two fatty amino groups per molecule.

It is another object of the present invention to provide a process of producing such compounds.

The invention is applicable to aldopentoses, aldohexoses and aldoheptoses. Suitable sugars which may be used in the present invention include galactose, glucose, gulose, idose, altrose, mannose, allose, ribose, xylose, lyxose, arabinose, and glucoheptose. By means of the present invention it is possible to introduce a fatty amino group onto each carbon atom of the aldose sugar.

The fatty amines which may be used include the primary amines, either saturated or unsaturated, containing from 8–22 carbon atoms. These may be single, isolated amines, or may be mixed amines derived from the fatty acids of a fat or oil, or from any selected group of such fatty acids.

In preparing these products it is desirable to use an excess of amine over the theoretical quantity of amine required to introduce the desired number of fatty amino groups into the sugar. Where it is desired to prepare more highly substituted products, it is preferred to use still a greater excess of amine than is required for the lower substitution products. For example, as high as 8 to 10 mols of amine per mol of sugar should be used where it is desired to introduce 5 or 6 fatty amino groups.

The temperature range suitable for reaction is approximately 40–100° C. Temperatures in excess of 100° C. tend toward excessive decomposition. A preferred range is 50–80° C. Lower temperatures within these ranges suffice for the introduction of two fatty amino groups into the sugar molecule. In order to obtain more highly substituted products it is necessary to employ temperatures within the upper portion of the ranges specified. The time required depends upon the temperature used and the product desired. To introduce 3 or 4 fatty amino groups requires about 4–6 hours at 60° C. To introduce 6 fatty amino groups into fructose, for example, may require from 6–8 hours at 75° C.

The reaction is preferably carried out in the presence of an aqueous solvent such as a mixture of water and a lower aliphatic alcohol. Alcohols such as methyl, ethyl, propyl, isopropyl and the like are suited for this purpose.

There are numerous possibilities for the structure of

2

these compounds and for the course which the reaction takes. The following reactions indicate the courses which the reaction may take and the products which may be obtained.

A continuation of this process leads eventually to

and all intermediate compounds are also formed. Cyclic products are also possible. Some of these are:

Example 1

45 A mixture of 3.6 parts of galactose, 32.3 parts of octadecylamine, 120 parts of isopropyl alcohol and 35 parts of water was warmed to 60° C. and allowed to cool to room temperature once for each of 17 days. It was then filtered and the product was recrystallized from alcohol. Analysis showed that it had been formed from the reaction of three mols of amine with one mol of sugar.

Example 2

55 A mixture of 3.6 parts of glucose, 32.3 parts of octadecylamine, 120 parts of isopropyl alcohol and 35 parts of water was warmed to 60–70° C. and allowed to cool to room temperature on each of 11 days. It was then filtered and the product was recrystallized from alcohol. Analysis showed that it had been formed by reaction of three mols of amine with one mol of sugar.

Example 3

65 During the recrystallization of the reaction product described in Example 2, another product was isolated. Analysis showed that it had been formed by reaction of four mols of amine with one mol of sugar.

Example 4

70 A mixture of 18.5 parts of dodecylamine, 1.8 parts of glucose, and 100 parts of 95% ethyl alcohol was stirred and heated at 60–65° for 11 hours and at 70–75° for 6 hours. It was then evaporated nearly to dryness under reduced pressure, chilled, filtered and washed with meth-

anol. A recrystallization from methanol then gave a product which, as analysis showed, had been formed by a reaction between 6 mols of amine and 1 of sugar.

I claim as my invention:

1. An aldose sugar-fatty amine reaction product, the aldose sugar containing from 5-7 carbon atoms, the fatty amine containing from 12-18 carbon atoms and the reaction product containing a number of fatty amino groups varying from 2 to the number of carbon atoms in the aldose sugar, one of said fatty amino groups being on the aldehyde carbon atom of said sugar.

2. Glucose-fatty amine reaction product, the fatty amine containing from 12-18 carbon atoms and the reaction product containing from 2-6 fatty amino groups, one of said fatty amino groups being on the aldehyde carbon atom of said sugar.

3. Galactose-fatty amine reaction product, the fatty amine containing from 12-18 carbon atoms and the reaction product containing from 2-6 fatty amino groups, one of said fatty amino groups being on the aldehyde carbon atom of said sugar.

4. Process of preparing aldose sugar-fatty amine reaction products containing at least 2 fatty amino groups which comprises reacting the aldose sugar with a fatty amine containing from 12-18 carbon atoms, the fatty amine being employed in excess of the theoretical quantity required for the introduction of the desired number of fatty amino groups, at a temperature within the range of 40 to 100° C.

5. Process of producing aldose sugar-fatty amine reaction products which comprises reacting an aldose sugar with a fatty amine containing from 12-18 carbon atoms in the range of 50 to 80° C. in the presence of at least 2 mols of amine per mol of aldose sugar.

6. Process of producing aldose sugar-fatty amine reaction products which comprises reacting an aldose sugar with a fatty amine containing from 12-18 carbon atoms, the fatty amine being employed in a molar ratio of at least 3 times that of the aldose sugar at a temperature within the approximate range of 50-80° C.
